JOURNAL WIPPING MEANS

James J. Hennessy, New York, N. Y.

Application February 19, 1934, Serial No. 711,933

12 Claims. (Cl. 308—80)

This invention relates to means for recovering excess lubricant supplied to journals, and particularly railway locomotive driving journals, much of which lubricant would otherwise escape 5 endwise of the journal and be centrifugally thrown off outside the journal box and lost.

In order to insure satisfactory lubrication of railway vehicle journals which support heavy loads, it is desirable to supply ample quantities 10 of lubricant to the journal at all times. Oil in sufficient quantities may be supplied to the bearing from above the journal by means of conduits leading through the crown bearing or from a reservoir carried in the lower part of the journal box 15 by means of a suitable pumping device such as that illustrated in co-pending application Serial No. 558,719, filed April 22, 1931 in the name of the present inventor.

Where the lubricant is pumped from a reservoir within the box itself, the pump may be adjusted to constantly maintain a pool of oil at 20 the surface of the journal providing so-called bath lubrication.

However, much of the oil supplied to the journal in such quantities is squeezed endwise beyond the bearing brass and, in the absence of suitable recapturing means, is thrown off and lost. The oil recapturing devices heretofore in use generally have not been efficient enough to prevent excessive oil losses where lubricant is constantly supplied to the journal by gravity or where bath lubrication is provided and, accordingly, such lubrication, though desirable from a mechanical standpoint, has not been considered practical.

It therefore becomes necessary to provide better means for recapturing lubricant than have heretofore been devised in order to permit the furnishing of relatively large quantities of oil to railway journals without substantial waste. 35 Moreover, with the use of efficient oil recapturing means a relatively simple inexpensive pump may be provided, or oil may be supplied conveniently and simply to the bearing by gravity from an overhead reservoir.

The main object of the present invention is to provide efficient means for recapturing oil escaping beyond the ends of the bearings of railway vehicle lubricated journals.

A more detailed object is to provide novel 50 means for recovering oil thrown off from the journal outside the journal box cellar and returning the same to a cellar within the box.

Another object is to provide an oil wiper for vehicle journals which may readily adjust itself 55 to the position and contour of the journal and

which may be easily replaced when worn or damaged.

These objects and others are attained substantially by the structure illustrated in the accompanying drawings in which—

Figure 1 is a vertical section through a locomotive driving box lubricator assembly and taken substantially along the axis of the journal.

Figure 2 is an end view of the assembly, portions being broken away and shown in section 10 substantially on the line 2—2 of Figure 1.

Figure 3 is a perspective view of one of the wiping devices, a portion being broken away.

Figure 4 is a transverse section through the center of the structure in Figure 3.

Figure 5 is a longitudinal section through a device somewhat similar to that in Figures 3 and 4 but modified as to a detail.

Figure 6 is a top view of another form of journal wiper.

Figure 7 is an end view of the device in Figure 6.

Figure 8 is a side view of the same.

In Figures 1 and 2 of the drawings, the invention is shown applied to a locomotive driving box having the usual heavy side walls 1 for engagement with the underframe pedestal (not shown) and receiving the crown bearing brass 2, the ends of which are undercut as at 3. Located in the lower portion of the driving box is a lubricant cellar 4 which is downwardly enlarged in its inner portion to form a lubricant reservoir 5. Within this reservoir is the body portion 6 of a lubricant pump which is actuated by the contact rod 7 extending through a tubular housing 8 within the cellar and engaging the hub 9 of the adjacent driver. It will be understood that lateral play of the driver and journal relative to the driving box will cause lubricant in reservoir 5 to be pumped through the screen 10, body 6, tubular housing 8, transverse passage 11, and upright delivery member 12 to the cup 13 where, during operation of the pump, a pool of oil is maintained in contact with or adjacent to the surface of the journal. Ball checks 14 and 15 are provided to trap the lubricant in cup 13.

Maintained adjacent the journal by means of a spring 16 is a lubricant distributing device shown in the present instance as formed of a series of strips 17 of suitable absorbent material 50 such as felt or celotex and intervening spacer strips 18 which may be of wood. At the ends of the lubricant cellar are baffle plates 19 and 20 for preventing the splashing out of lubricant over the top edges of the cellar end walls 21 and 55

22 which are slightly spaced from the journal as shown at 23 in Figure 2.

The details of the driving box, pump, and oil distributor shown do not in themselves constitute the present invention. The pump is more clearly described in the above-mentioned co-pending application Serial No. 558,719.

In order to prevent lubricant from escaping over the side walls 24 of the cellar, these walls 10 extend into grooves 25 formed in the side portions 1 of the driving box immediately beneath the side edges of the bearing brass 2. This feature is covered in co-pending application Serial No. 728,894 filed June 4, 1934 by the present inventor. At the inner end of the box is provided a closure member 26 surrounding the journal and including a portion 28 forming a cover for the reservoir 5. Closure member 26 includes a felt strip 27 with its inner edge bent 15 over as at 29 and snugly engaging the journal to prevent the loss of lubricant through this portion of the box.

It has been observed that lubricant squeezed out from under the bearing tends to form in a 25 ring adjacent the end thereof and is centrifugally thrown off from the journal in the form of drops. In order to bring this oil ring within the end wall 22 of the cellar, the brass is undercut as at 30 3. However, due to the lateral play of the journal, some of the accumulated drops will be thrown outside the cellar wall. In order to recover the oil thrown off the journal outside the cellar and which would be otherwise lost, a series 35 of cooperating wiping and collecting devices A, B and C are provided for wiping the journal, and particularly the portion thereof outside the cellar outer wall 22, and returning the recovered lubricant to the cellar.

The wiper A, Figures 3 and 4, comprises an 40 elongated box-shaped housing 30, which extends through and is rigidly secured to the end wall 22 of the lubricant cellar. The top wall of the housing is longitudinally slotted to receive the journal wiping rib 31. The rib 31 is enlarged 45 in its lower portion to form shoulders 32 for seating against the slotted top wall of the housing 30. At the bottom of the housing is a cup-like depression 33 seating the spring pressed 50 plunger 34 for urging the rib wiper 31 towards the journal. Preferably the ends of the enlarged lower portion of the ribbed wiper are rounded as at 35 to facilitate insertion thereof past the plunger 34, this plunger in the assembled device seating in a depression 36 to 55 yieldingly resist withdrawal of the wiper. Preferably the rib 31 engages the journal along line inclined to the horizontal, as indicated in Figure 2, so that the recaptured lubricant will be drained along the upper surface of the rib into 60 the cellar.

In Figure 5 is shown a ribbed wiper device 37 mounted in housing 38 similar to that in Figures 3 and 4, but the wiper is urged towards the journal by means of a bent flat spring 39 normally seating in a depression 40 in the under-surface of the wiper. In this as well as the previous form the wiping rib is yieldingly and adjustably maintained in contact with the journal.

The wiping device B, detailed in Figures 6, 7 70 and 8, comprises a body portion including ribs 41 with upper journal engaging surfaces inclined inwardly and downwardly. Lubricant recovered by ribs 41 is collected in inclined troughs 42 and the space between the ribs and drained by 75 gravity to the transverse outlet trough 43 which

is inclined downwardly from the center towards each side. At the inner end of the body portion is a curved arm 44 arranged to seat against and extending partially around the surface of the journal. This arm serves as a stabilizer for 5 the wiper.

Seated in a hemispherical bearing 45 in the undersurface of the wiper body is a pin 46 (Figure 2) extending through a perforation in the splash plate 20 and urged upwardly by a coiled 10 spring 47 seated against a washer 48 held against movement along the pin by means of a cotter key 49. A spacer bushing 50 surrounds the pin 46 and has slots 51 for accommodating the cotter 49. The wiper body is thus yieldingly and adjustably 15 maintained in contact with the journal.

At the sides of the wiper B are upright bolts 52 seated on the bottom of the cellar and extending through the splash plate 20 and terminating in close proximity to the journal. 20 These bolts serve to relieve the wiper mechanism of excessive vertical loads in case the driving box is jacked up as for renewing the bearing brass.

The wipers A are located closer to the side 25 edges of the bearing than the wiper B and, accordingly, these need not extend quite as far beyond the end wall of the cellar as the latter in order to recover oil moved away from the end 30 of the bearing by longitudinal play of the journal. However, it is desirable that all of the wipers extend beyond the end of the end of the bearing.

There will be a tendency of lubricant to travel 35 longitudinally within the grooves 25 in the sides of the driving box and in order to recover lubricant in these grooves which may travel beyond the end wall of the cellar, the angle-shaped cups C are provided which extend to the ends of the grooves. Each of these cups is formed of a metal strip bent in the form of an angle and its side 40 edges buttwelded to the end wall of the cellar and underlying the end of the depending lip of the box groove 25. Collected lubricant is drained through the hole 53 in the cellar wall. The collecting devices C are illustrated and claimed in 45 the above-mentioned co-pending application Serial No. 728,894.

With the use of the oil recovering devices herein described, substantially all the lubricant 50 escaping beyond the end of the bearing is recovered, only just enough being allowed to escape to properly lubricate the hub face and box hub liner. Each of the wipers is yieldingly mounted on the end of the cellar and arranged 55 to collect lubricant on the journal and return the same into the cellar by gravity. With the use of these recovery devices bath lubrication of the journal is made practical and also it is possible to supply oil to the journal by means of a 60 simple inexpensive gravity feed without the danger of excessive losses.

Various details of the structures as illustrated and described are not essential and these may be modified as will occur to those skilled in the art 65 and exclusive use of all such modifications as come within the scope of the appended claims is contemplated.

I claim:

1. Railway journal lubricant wiping means 70 applicable to the end portion of a journal box cellar member to underlie the journal on both sides of an end wall of the cellar and including a rib element disposed to engage the journal along a line extending longitudinally thereof and having an 75

inclined recessed passage for conducting the recovered lubricant along said element.

2. In a railway journal lubricating cellar, an end wall shaped to clear the journal, a housing carried by and extending through said wall and having a slotted top portion, an elongated member in said housing and having a journal wiping rib extending through said top portion, and spring means in said housing for urging said rib towards the journal.

3. Structure as defined in claim 2 in which said ribbed member is renewable, and provided with a hollow in its undersurface for seating said spring means to yieldingly maintain the same properly assembled with said housing.

4. In combination, a railway journal lubricating cellar having an end wall shaped to clear the journal, and a journal wiper comprising a body portion mounted in said cellar and extending through said wall and having a rib for wiping lubricant from the journal and an inclined trough for conducting the recovered lubricant from outside said wall into said cellar.

5. Structure as defined in claim 4 in which said body portion is adjustably and yieldingly carried in said cellar so as to conform with the journal.

6. As a new article of manufacture, a railway journal lubricant wiper unit comprising a body portion arranged to be applied to and removed from and to be supported by a lubricant cellar wall adjacent the journal and having a wiping edge for engaging the journal, and a curved arm arranged to seat against and extend partially around the journal transversely of the length of said edge for positioning said edge.

7. In combination, a railway journal lubricant cellar having an end wall and a transverse flange projecting inwardly thereof, and a journal wiper comprising a body portion with an element for engaging the journal and structure support-

ing said body portion from the floor of said cellar and extending through and stabilized by said flange.

8. Structure as defined in claim 7 in which said flange constitutes a splash plate for preventing loss of lubricant over said end wall and said wiper is yieldingly supported substantially above the cellar floor. 5

9. The combination of elements specified in claim 7 in which said supporting structure is 10 arranged to yieldingly support said wiper body portion.

10. In a railway journal lubricator, a cellar having a transverse end wall with a top contour for fitting around the journal, there being an 15 opening in said wall, a member extending through said opening and projecting inwardly and outwardly of said wall and seated on an upwardly facing portion of said wall forming the lower edge of said opening, and a separate wiper 20 element extending upwardly from said member for engagement with a journal to which the lubricator is applied.

11. A structure as described in claim 10 in which the wiper element is yieldingly supported 25 in the member extending through the journal wall.

12. As a new article of manufacture, a railway journal lubricant wiper device comprising a body having an elongated downwardly facing recess 30 disposed to fit over the wall of a lubricant cellar, there being elongated upwardly facing curved wings extending in the same general direction of said recess to engage a journal, and an upwardly facing ridge of restricted width extending downwardly toward said wings for wiping surplus lubricant from the journal, there being a trough adjacent said wings for draining lubricant gathered by the wiper downwardly and inwardly of the cellar to which it is applied. 35 40

JAMES J. HENNESSY.
